United States Patent Office.

JAMES McLAUGHLIN, OF DUNCANNON, PENNSYLVANIA.

Letters Patent No. 60,920, dated January 1, 1867.

IMPROVED CAR-COUPING.

The Schedule referred to in these Letters Patent and making part of the same.

TO ALL WHOM IT MAY CONCERN:

Be it known that I, JAMES McLAUGHLIN, of Duncannon, in the county of Perry, and State of Pennsylvania, have invented a new and improved Car-Coupling; and I do hereby declare that the following is a full, clear, and exact description thereof, which will enable others skilled in the art to make and use the same, reference being had to the accompanying drawings, forming part of this specification, in which—

Figure 1 is a side sectional view of my invention taken in the line xx , fig. 2.

Figure 2 is a plan or top view of the same.

Similar letters of reference indicate like parts.

This invention relates to a new and improved car-coupling, of that class which are self-connecting or self-coupling, and it consists in a novel construction and arrangement of parts, as hereinafter fully shown and described, whereby a very simple and efficient car-coupling of the class specified is obtained.

A A' represent draw-heads, which may be attached to the car in the usual or in any proper manner, and B are coupling-pins, which are fitted vertically in the front parts of the draw-heads and allowed to pass down through the bottom plate α of the same in order to secure the link or shackle C to the draw-heads and form a connection between the same. On the upper surface of each draw-head there is a slide, D, which works in a socket, E, through which the coupling-pin B also passes. This slide D is connected by a rod or bar, E*, to a weight, F, which is suspended in the upper part of a framing, G, on the draw-head by pivots b , as shown clearly in fig. 1. This suspended weight F has a tendency to keep the slide D shoved forward in the socket E; and, when the coupling-pin B is raised, the weight F forces the slide D underneath it, and the latter holds the pin up. The slides D have each a pendent pin, e, attached, and these pins extend down into the draw-heads through oblong slots d in the upper plates thereof.

From the above description it will be seen that where the coupling-pin B of one draw-head is held in an upward position by the slide D underneath it, and the link or shackle C of the other draw-head passes into it, the pendent pin e of the slide D, which supports the elevated pin, will be acted upon by the entering link or shackle and the slide D forced back so that the pin may drop through the link.

Each draw-head is provided with a link or shackle, C, one only being used, the idle link being fitted around pins d d' in the draw-head, the front pin d extending the whole height of the draw-head and serving as a draw-pin. Directly back of the pin d of each draw-head there is a bearing, e, which prevents the link or shackle being forced back in coupling.

I claim as new, and desire to secure by Letters Patent—

The slide D provided with the pendent pin e and connected with the suspended weight F, in connection with the coupling-pin B and link or shackle C, all arranged to operate substantially as and for the purpose herein set forth.

JAMES McLAUGHLIN.
